UNITED STATES PATENT OFFICE.

CHARLES P. STANBON, OF SAUGUS, MASSACHUSETTS, ASSIGNOR TO UNITED SHOE MACHINERY COMPANY, OF PATERSON, NEW JERSEY, A CORPORATION OF NEW JERSEY.

FOLDING-MACHINE.

1,120,556.

Specification of Letters Patent.

Patented Dec. 8, 1914.

Application filed April 17, 1908. Serial No. 427,638.

To all whom it may concern:

Be it known that I, CHARLES P. STANBON, a citizen of the United States, and a resident of Saugus, in the county of Essex and State of Massachusetts, have invented an Improvement in Folding-Machines, of which the following description, in connection with the accompanying drawings, is a specification, like letters on the drawings representing like parts.

This invention pertains to folding machines of that type wherein the stock is moved progressively past folding instrumentalities which act upon successive portions thereof. For example, machines embodying this invention may be especially adapted for folding the edges of vamps, quarters and other parts of shoe uppers.

It is an object of the invention among others, to produce a machine which shall be of simple construction and accurate, even and uniform in its operation.

An important feature of the invention consists broadly in the provision, in a step-by-step folding machine, of a creaser arranged to define the fold line and a folder movable to fold the work over the edge of the creaser. It has been found that a machine embodying members of this character possesses many advantages over folding machines heretofore employed. For example, each short portion of the margin of the work operated upon is positively bent by the folder about a well defined stationary axis formed by the creaser so that a folded margin is produced which is of the uniform width desired. Moreover this result is secured regardless of variations in the quality of the material being handled or of irregularities incident to seams intersecting the edge to be folded or the like.

Another very important advantage derived from the use of a creaser and folder of this character is that work having edges sharply curved may be operated upon to good advantage. This results partly from the fact that, since the folder and creaser operate successively upon relatively short portions of the margin, the work may be swung between these operations to present its curved margin in the proper relation to the creaser and folder. Moreover, the folder and creaser carry the folding operation upon each short length of the margin

to such a point that the work may be advanced to the fold presser without danger of the margin straightening out in the meantime.

All of the features above discussed contribute to render the machine capable of operation at a high speed and this is another important advantage resulting from the construction of the present invention.

Another feature of the invention, relating more particularly to the creaser, consists in so mounting the latter that it shall be capable of a yielding movement obliquely away from the fold line. Such an arrangement insures the formation of a straight folded edge regardless of variations in the thickness of the material, the axis or vertex of the fold being shifted away from the edge when a thick portion is encountered thus compensating for the added thickness which would otherwise form a bulge. In the machine herein shown, the folding operation is completed by pressing or hammering the folded margin upon the body of the work.

In this connection another feature of the present invention consists in the provision of a fold presser and an associated actuating or carrying member therefor positively connected below the work support to the driving mechanism of the machine and having a yielding and adjustable connection with the fold presser. Such construction enables the operator conveniently to regulate the action of the presser to a nicety. This is brought about by arranging the yielding and adjustable connection independently of the mechanism for operating the carrying or actuating member and within convenient reach of the operator. At the same time the operating connections may be located beneath the work support where they will in no way obscure the work or interfere with its presentation to the folding instrumentalities.

Still another feature of the invention relates to the construction of the snipping knife and to novel means for throwing the knife into or out of operation. As herein shown the mechanism for controlling the snipping knife is so related to the mechanism for starting and stopping the folding instrumentalities that both are controlled by a single treadle, the initial movement of

the treadle being utilized to throw into operation the folding instrumentalities while a further depression of the treadle brings the snipping knife into action. This arrangement permits the elimination of a separate treadle formerly used for controlling the snipping knives and so renders the machine under a more perfect control of the operator.

These and other features of the invention will be best understood and appreciated from the following description of a preferred embodiment thereof selected for purposes of illustration and shown in the accompanying drawings.

In the drawings, Figure 1 is a side elevation of the illustrative machine, partly in section and having portions of its hollow frame casting broken away to show inclosed parts; Fig. 2 is a section on the line 2--2 of Fig. 1; Fig. 3 is a plan view of the immediate illustrative folding instrumentalities; Fig. 4 is a detached detail end elevation (viewed from the left in Fig. 1) of one of the folding devices and its actuating mechanism; Fig. 5 is a detail side elevation on an enlarged scale of the folding device shown in Fig. 4; Fig. 6 is a detail section on the line 6--6 of Fig. 1; Fig. 7 is a detail section on the line 7--7 of Fig. 1; Fig. 8 is a detail section partly in elevation on the line 8--8 of Fig. 3; Fig. 9 is a detail section on line 9--9 of Fig. 3; Figs. 10, 11 and 12 are detail sections on a line 10--10 of Fig. 3, showing successive steps in the preferred folding operation of the machine shown in Fig. 1; Fig. 13 is a detail plan showing the relative positions of the folder and the creaser when said folder is in its forward position, the leather being indicated at 203, and Fig. 14 is a plan of the folder.

Referring now to Fig. 1, the illustrative machine has a work table 20, upon which the work rests and across which the work may be moved in any practicable manner as by mechanical feeding means, such as feed wheels 22 and 24. The wheel 22 is mounted upon the end of its driving shaft 26, which is given preferably an intermittent feeding movement permitting the stock to present successive portions to the folding instrumentalities and dwell from time to time to permit successive folding operations to take place. The preferred method of communicating this intermittent movement to the feed wheel 22 and shaft 26 is by a clutch device shown in Fig. 7, the latter being a detail section on the line 7--7 of Fig. 1, as viewed from the left. Fixed upon the shaft 26 is a disk 28 of a roller clutch encircled by the annulus 29. A link 30 connects the annulus 29 with a pin 31 adjustably clamped (by a screw 32) to a cam operated arm 33, fulcrumed at 34 to a bracket on the machine frame. The arm 33 has a cam roll 36 to en-

gage an eccentric 38 mounted on the power shaft 40 of the machine. A spring 42 serves to hold the roller 36 in engagement with its cam. The operation of these specific parts is such that each revolution of the power shaft 40 rocks the arms 33 counterclockwise about its pivot 34; thereby (through the link 30) rocking the annulus 29 in the direction of the arrow, Fig. 7 and, said annulus thereupon clutching with the disk 28, the shaft 26 and feed wheel 22 are rotated through a feed step. Subsequent travel of the shaft 40 permits the arm 33 to return clockwise, thereby returning the annulus 29 also clockwise to position to renew its clutching grip on the disk 28. The disk 28, shaft 26 and feed wheel 22 are prevented from accompanying the annulus 29 in its return movement by a spring pressed plug 44 shown in Fig. 1, which bears yieldingly against the inner face of the feed wheel 22 and acts as a drag thereupon which overcomes any frictional tendency of the annulus 29 to bind with the disk 28 except when the two enter into positive clutching engagement through the rolls.

Referring again to Fig. 7, by loosening the screw 32 the pin 31 may be slid axially, so as to increase or decrease the distance of its pivot 46 from the fulcrum 34 of the arm 33. This varies the travel of the pivot 46 during the periodical rocking of the arm 33 and thereby determines adjustably the travel of the annulus 29 and the length of feed step actuated thereby.

The arrangement just described is particularly desirable in connection with folding machines of the type under discussion, since it affords a simple but effective means for obtaining the desired feed and at the same time is readily adjustable to permit different lengths of feed steps. There is a desirable cooperation between these feeding features and the snipping or edge slitting means presently to be described, since by varying the feed the edge may be slit at different intervals to suit varying conditions, as of curvature in the edge of the stock.

Fixed upon the shaft 26, is a bevel gear 50, meshing with a bevel gear 52 upon a countershaft 53 having at its opposite end a bevel gear 54 driving an auxiliary feed wheel shaft 55 which has at its lower end the feed wheel 24. The shaft 55 is appropriately journaled in a removable casting 56, pivotally supported on the main frame by a pin 57. The casting 56 with its shaft 55 is free to rotate about the pin 57, save for the fact that it is yieldingly restrained by a leaf spring 58 engaging a notch in the casting 56. The spring 58 is appropriately mounted on the main frame and its tension is adjustable by means of a screw 59 bearing upon one end thereof. The casting 56 and its shaft 55 can be rocked on the pin 57 clockwise in Fig. 1

(to lift the feed wheel 24 away from the wheel 22) by means of a hand lever 60 engaging at its toe end a sliding pin 61 which abuts against the lower end of the casting 56. The spring 58 holds the casting 56, shaft and feed wheel 24 yieldingly in the position determined by the adjustable stop screw 62, which forms a rest for the lower part of the casting 56. Thus, by adjusting 5 the screw 62 the feed wheel 24 may be spaced at a greater or less distance from the wheel 22. By turning the screw 59 the yielding pressure on the work of which the wheel 24 is capable (by reason of the spring 58) 10 may be varied at will.

Either with or without the features of adjustment just described, it is preferred that the wheel 24 be adjustable axially and, for illustration, this is provided for by permitting the shaft 55 endwise movement in its journals on the casting 56. The bevel pinion 64 by which the shaft 55 is driven, is splined to the latter; and between its hub and a collar 65 fixed upon the shaft 55 is interposed a 20 compression spring 66 tending to force the shaft 55 and feed wheel 24 downward. The collar 65 normally rests against the end of a sleeve 67, threaded along part of its length into the casting 56. By turning the sleeve 25 67 the shaft 55 may be positively adjusted axially against the pressure of the spring 66. The sleeve 67 may be held in adjusted position by a set screw 68.

It will be observed that the wheel 24 may 30 be adjusted so that its position of nearest approach to the wheel 22 may be positively determined axially by adjusting the sleeve 67; and circumferentially about the pin 57 by adjusting the screw 62. At the same time 40 the wheel 24 may be yieldingly displaced from its position either axially against the spring 66 or circumferentially against the spring 58. These particulars are of advantage in connection with a preferred co- 45 operation between the feed wheels about to be explained. As shown in Fig. 1 and enlarged in Figs. 10, 11 and 12, the wheel 22 has a radially projecting peripheral flange 70, which at its intersection with the cylindrical surface of the wheel supplies an angular recess into which the wheel 24 may tuck or crease the work, thereby contributing to determine the vertex of the fold. To 50 suit this purpose the periphery of the wheel 24 is preferably acutely angular; and it may be toothed or roughened to assist in gripping the work. Fig. 10 shows one way in which the wheels 22 and 24 may coöperate by creasing the work. To produce this effect 55 it is preferred to adjust the screw 62, so that the work will be continuously and securely pinched or gripped (through the spring 58) between the two feed wheels, the spring 58 having the effect of pressing the wheel 24 in 60 substantially the direction of the arrow 72

in Fig. 10. The effect of this coöperation may be to crease the work more or less deeply or, if desired, to incise or otherwise demark the same so as to determine the vertex of the fold.

In connection with a creasing or other demarking operation such as has been described, the adjustability of the creasing device 24 exemplified by mounting it on the pivot 57 is of advantage. If, as is frequently the case, the work have a seam or other abnormal thickness at some place on its edge, said thickness when fed between the wheel 22 and the creasing device 24, will tend to rock the latter on the pivot 57 slightly upwardly and toward the left in Fig. 1. This may have the effect of moving the creasing edge of the device 24 farther from the edge of the stock, thereby causing the line of the fold vertex to bend inwardly more or less according to the thickness of the seam. Thereupon when the work is folded on the concaved vertex line so determined, the added thickness of the seam at the folded edge will be received in the concavity formed by shifting the vertex inwardly; and thereby the folded edge will be made straight and smooth regardless of the abnormal seam thickness which would otherwise cause a bunch or bulge upon the folded edge.

By reference to Fig. 3, it will be seen that the operator who views the machine substantially from a position at the bottom of the sheet of Fig. 3, finds the coöoperating feed wheels 24 and 22 readily visible so that he may guide the work carefully with reference to the crease made thereby. The preferred continuous engagement of the work by the feed wheels may supply a mechanical control thereof relieving the operator very considerably from the necessity for careful and skilful attention to the folding.

To insert the work (see Fig. 1) the hand lever 60 may be depressed to lift the wheel 24. Thereupon the work is placed with its edge resting, inclined, upon the face of a plow 75, the edge of the work resting against an edge gage 76. The latter may be supplied upon a spring finger 77, fixed at its upper end to a clamp collar 78, encircling and clamped to a downwardly extending part of the casting 56. This spring finger 77 may be appropriately bent to form both the edge gage 76 and a face gage or guard 80. A part of the spring finger 77 may project into a slot or other seat in the plow 75, to provide a steadyng member 81, as shown in dotted lines in Fig. 10. The spring finger 77 by its face guard 80 may press upon the edge of the work and serve to smooth the same and hold it snugly against the plow 75. When placed in initial position the edge of the work is already turned at an angle to the body of the work 130

and as it progresses the vertex of the crease may be defined by the coöperating feed wheels, while at the same time the edge slides along the face of the plow and is turned farther and farther toward the wheel 24.

Referring now to Fig. 3, after the advance end of the work has passed the end of the plow 75, it is engaged by a folding device 85 (Fig. 5). When in its normal inactive position the folder 85 stands somewhat to the rear of the line of travel of the work. When the work edge, already partially turned by the plow 75, stands in front of the folder 85, the latter is advanced toward the line of feed to turn the edge still farther over. Preferably the device 85 merely turns the edge without pressing it; thereby only lightly engaging the work without having any material tendency to stretch the same. Referring to Fig. 3 the folder 85 is there shown in inactive position. Its movement takes place in a generally horizontal direction toward the left in Fig. 3. Thus its active relationship with the feed wheel 24 is such that it tends to fold the work over the lower edge of the wheel 24; thus assisting in determining the fold vertex.

A practicable organization of means to operate a folder 85, is shown in Figs. 1, 4 and 5. The folder 85 itself is mounted upon a pivot pin 86, appropriately seated in the main casting, as shown in Fig. 1. The lower end of the folder has a toe which enters a notch in a shaft 88, extending toward the rear of the machine and mounted so as to be capable of sliding endwise. Between a collar 90 on the end of the shaft 88 and a fixed part of the main frame, is interposed a compression spring 92 having a constant tendency to move the shaft 88 to the right in Fig. 1 and to rock the folder 85 contra clockwise, *i. e.*, to move its acting end toward the work to perform its folding office. Thus the folder may act upon the work yieldingly under the impulse of the spring 92. Fixed upon the shaft 88 is an arm 93 having a roller 94 engaging a cam 95 on the power shaft 40. During each revolution of the latter the cam forces the arm 93 and shaft 88 toward the left in Fig. 1 to rock the folder 85 away from the work; and also permits the spring 92 to move the shaft 88 toward the right to effect the operation of the folder 85. The arm 93 is adjustably secured by a set screw on the shaft 88, so that the folder 85 may be adjusted with relation to the work table 20 and the other parts. Also, the spring engaging collar on the shaft 88 is adjustably secured by a set screw so that the tension of the spring 92 may be varied. When the work has been acted upon by the devices already described it may be further treated by a fold presser 100. The presser 100 is

shown in end elevation in Fig. 2, in detached side elevation in Fig. 8, and in different working positions in Figs. 11 and 12.

Referring now to Fig. 8, the presser 100 consists of a lateral projection from a sleeve 101 mounted so as to be capable of sliding vertically on a pin 102 threaded into the presser carrier which comprises a plunger 103; a spring 104 being interposed between the shoulder under the head of the threaded pin 102 and the top of the presser 100. The upper end of the plunger 103 is cut away to receive and form a housing for the sleeve 101 of the presser. The plunger 103 is vertically reciprocated to cause the presser 100 to press the fold, as shown in Fig. 8; and this pressing action is cushioned by the spring 104 which permits the presser to yield in response to abnormal thicknesses in the stock and to prevent extreme compression sufficient to injure the work. By screwing the threaded pin into and out of the plunger 103 the compression of the spring 104 may be adjusted as desired. The rear squared face of the sleeve 101 bears against a correspondingly squared face or part of the plunger 103, and this serves to prevent rotation of the presser 100 on its supporting pin 102.

Referring now to Fig. 2, the plunger 103 has a downwardly extending part 106, upon which is threaded a casting 107 having therein a horizontal slide way for a block 108 pivoted upon an eccentric pin 109 projecting from the end of the power shaft 40. Lock nuts 110 and 111 threaded on the plunger part 106 confine the casting 107 between them; and a set screw 112 may be used to secure the casting 107 securely in position. By loosening the set screw 112 and turning the lock nuts in the appropriate direction the plunger or presser housing may be raised or lowered and thus the vertical position of the presser may be adjusted. With this arrangement, each rotation of the power shaft 40 causes one complete vertical reciprocation of the plunger, and thereby depresses the presser 100 yieldingly through the agency of the spring 104. The time relation which is preferred to prevail between the folder 85 and the presser 100 is such that the former performs its office of turning over the edge of the work more or less in advance of the descent of the presser to complete and press the fold; also it is preferable that the folder 85 dwell in its final folding position for a short period, so as to maintain the fold in proper condition, awaiting the final action of the presser 100. Likewise the folder 85 may retreat from active engagement with the work before the presser is elevated to inactive position.

Referring now to Fig. 3 the folder 85 preferably acts close along side the presser 100.

100 and the latter may have a projecting portion giving its pressing surface a near approach to the feed wheel 24 and increasing its effective area. It is frequently desirable to employ snipping or slitting means to make cuts in the edge of the work to provide against crimping or puckering in folding a curved edge, as is well understood in the art. The present illustrative machine is 10 provided with snipping means exemplified by a knife 120, shown in Figs. 1, 3 and 12.

Referring now to Figs. 1 and 12, the cutting edge of the knife 120 is inclined so as to be parallel to part of the face of the plow 75, the latter conveniently serving as a cutting bed. As presently described, the knife moves preferably in a path at an angle to its cutting edge and the cutting bed as, for instance, in a vertical path in Fig. 1. There- 20 by, the knife may be caused to cut obliquely through the work from one surface to the other, so as to give a species of drawing cut, which makes a cleaner slit and occasions less wear on the knife. That particular part of 25 the plow 75 which is utilized as a cutting bed is inclined, and to suit this inclination the knife is set obliquely in its holder. As shown in section in Fig. 9, the knife shank 120 rests in a dovetailed seat supplied upon 30 one side by part of the knife plunger and upon the other side by a removable clamping plate 121 and held in place by a screw 122. In the specific machine as in other machines 35 of the same general type already known in the art the edge of the work is ordinarily partially turned over at the time when the knife acts. Usually also that part of the work edge which is cut by the knife is somewhat lifted from the plane of the body of 40 the work. Under such circumstances, if the cutting bed be in the plane of the work body, as on the work supporting table, the snipping operation will tend to pull down and flatten the work edge against the cutting 45 bed, thereby stretching the edge. To express it differently—part of the edge having been turned over and pressed down, the remainder of the edge is turned with a progressively lessening curve toward the 50 flat unfolded part of the edge. If the knife operates to cut against a bed in the plane of the body of the work at any point between the flat unturned edge and the completely folded part of the 55 edge, the partly lifted edge is forced back upon the bed and in accommodating itself to such a position the work is stretched. This is especially true if the knife be dull, in which case it exerts a pull on the stock 60 before making its incision. When thus stretched, for example when working on a vamp throat, the edge of the throat is longer than it is intended to be and is likely to pucker in assembling the vamp and 65 quarters.

The above described difficulties are avoided in the machine of the drawings, by having the cutting bed inclined to suit the lifted or partially turned position of the work edge prevailing at the point where the knife 70 acts. Thus the work edge is supported in its natural position, so that no stretching results. By this means the work edge may be cut close to the completed fold, if desired, even though the edge may be very consider- 75 ably raised above the plane of the body of the work. This admits of a very compact organization of the machine, which is of course desirable. The upper part of the knife plunger may consist of a sleeve 124 80 encircling the plunger proper 126. Between appropriate shoulders on the sleeve 124 and plunger 126 is interposed a compression spring 127 which holds the upper extremity of the sleeve, against the head of a screw 85 128 threading into the plunger 126. As the plunger moves vertically downward, the knife carried on the sleeve 124 is forced rigidly to its cutting operation by the head of the screw 128, but for purposes of adjustment the spring 127 causes the sleeve and knife to follow the screw 128 as it is turned upwardly and downwardly on the plunger 126.

Referring now to Fig. 2, the plunger 126 90 is suitably mounted for vertical movement in the main frame casting along side the presser plunger 106. The knife plunger is normally upheld by a compression spring 130 interposed between part of the frame 100 and a collar on the plunger; and said spring serves to hold a second collar 131 up against part of the frame which determines the uppermost limit of movement of the plunger. To give the plunger 126 and knife the 105 desired vertical reciprocation for cutting, the plunger 126 may be connected to the presser plunger 106 which is preferably continuously reciprocated and supplies a convenient source of power. For this purpose, the casting 107 of the plunger 106 has a heel 133 projecting laterally toward the knife plunger 126 in position to engage a spring latch 135 on the latter. This latch is seated in a radial recess in the plunger 126 and is 110 pressed outwardly therefrom by a spring (not shown) except when prevented as presently described. Thus, in Fig. 2, when the heel 133 descends in the movement of the presser, it may strike against the lower tooth of the latch 135 and carry down the knife plunger 126 and knife against the tension of the spring 130. It is not always necessary to slit an edge to be folded, and at 115 times the knife or other snipping means may as well be idle. For example, in folding a shoe vamp, it is not necessary to snip any part, usually, except the throat. Accordingly it is convenient to supply means for 120 interrupting the operation of the knife at 125 130

will. This may be done in the illustrative machine by moving the spring pressed latch 135 into or out of the path of the heel 133. The position of the latch 135 can be readily controlled by means of a pin 140 (Figs. 1 and 2) which is movable axially into and out of the path of the inclined upper surface of the latch. When the pin 140 is in the path of the latch (the plunger 126 being down), ascent of the plunger will force the latch against the pin 140 and thereby the latch will be retreated into its seat and removed from position to engage the heel 133. If then the pin 140 be withdrawn from engagement with the latch 135, the latter will be forced out by its spring and will presently be engaged by the heel 133. The pin 140, as shown in Fig. 1, is mounted in the frame casting and is normally pressed toward position to engage the latch 135 by a spring 142. This spring is opposed to withdraw the pin 140 by means of a cam 144, which, as shown in Fig. 6, straddles the end of the pin 140 and bears against a nut threaded on the end thereof. When the cam 144 is depressed, it presses the pin 140 toward the right in Fig. 1 and removes the latter from interference with the latch 135. The cam 144 is controlled by means of a lever 146 normally upheld by a spring 150. A treadle or other governor may be connected to the lever 146 as by a chain 152. The lever 146 is fixed upon the clutch controlling shaft 148, and accordingly when the lever is rocked, the shaft is also rocked, thereby causing a cam arm 160 having a cam 161 fixed on the shaft 148 to rock and press a driving clutch member 162 toward the left in Fig. 1 into engagement with the driven clutch member 161 fixed upon the power shaft 40. A spring 166 interposed between the hubs of the two clutch members serves normally to hold them apart and out of driving engagement.

Referring again to Fig. 6,—in the movement of the lever 146, it is initially effective to throw the clutch and start the operation of the machine. This office is completed during only the first part of the throw of the lever during that time the lever is preferably not moved far enough to shift the pin 140, release the latch 135 and start the cutting operation. Further movement of the lever, however, will accomplish this. Thus, if a treadle be connected to the chain 152, a partial depression of the treadle may start the machine, and then, as occasion requires, the operator may further depress the treadle slightly during such time as he desires the cutter to operate. In this way the two operations of starting the machine and governing the snipping may be controlled by a single means, thereby effecting a great saving in time by avoiding a shift from one means to another.

65 To summarize, the operation of the spe-

cific machine shown in the drawings is as follows: The operator depresses the handle 60 to elevate the feed wheel 24 and facilitate introduction of the work, which he places in position to be engaged between the two feed wheels, with its edge against the edge gage 76 and beneath the face gage 80. Thereupon the handle 60 may be released, permitting the feed wheels to resume their active positions preferably immediately engaging the work. When positioned the edge of the work may stand obliquely with relation to the work supporting surfaces of the machine, against the plow 75, thereby being lifted or turned in the initial stages of the folding operation. By depressing his treadle (not shown) he starts the machine through the chain 152 (Fig. 1), thereby initiating the feed of the work. During the feed the advance end of the work may be turned progressively to greater obliquity to the work supporting surfaces by the preferred conformation of the plow 75; and by the time the work reaches the advance extremity of the plow, it may be turned toward the body of the work somewhat beyond a perpendicular relation. This places the edge conveniently in position to be acted upon by the folding device 85, which operates between the feeding steps of the work while the latter is temporarily at rest. During these initial operations of the machine the conjoint action of the work supporting means and the device 24 serves to crease or otherwise mark a line normally substantially parallel to the edge of the work; and this may serve to determine definitely (if desired, substantially independently of the operator's skill) the vertex, or fulcrum so to speak, upon which the edge is turned. For instance, by making an actual crease, the creased line may offer less resistance to folding than other parts of the work, so that the subsequent operations may insure turning the edge about said line as an axis. As illustrated in Fig. 11 the folding device 85 has turned over the work edge somewhat in advance of the point engaged by the creasing device 24; and preferably the office of the member 85 is merely to turn the edge toward its final position without pressing it, the pressing being effected upon further progress of the work by the reciprocating presser 100 shown in active position in Fig. 12. In preparation for the pressing operation, the edge folding device 85 preferably advances to turn the edge over while the presser 100 stands in an elevated position; and the device 85 may dwell in the position shown in Fig. 11 until the presser has descended and engaged the fold. Thereupon both the device 85 and the presser 100 may retreat, leaving a portion of the fold pressed and completed. During these operations and successive feed-

ing steps of the work, the latter may slide over the face of the plow and receive continuous support therefrom until acted upon by the edge turning device—the position of the work edge being always such as it would naturally assume between completely folded parts and the unturned fresh edge, if no controlling devices were acting upon it. Having this natural position and being supported therein by the plow 75, its edge may be cut without any danger of stretching. During the feed of the work the edge folding device 85 is preferably retreated from the line of feed, so as not to interfere with the travel of the work, leaving the same a substantially free uninterrupted path.

At any time during the above described operation of the machine, the operator by merely depressing his treadle may start the cutting action of the knife and may interrupt it as desired by a foot operation, leaving his hands entirely free to guide the work.

A machine embodying features of this invention has many advantages which are novel in the art. For example; the feeding means may govern the work continuously. There may be provisions for creasing or otherwise demarking upon the work the vertex of the fold so as to determine the same mechanically. The work may be so governed and acted upon that there is no tendency whatever to stretch the edge. The cutting operation may be readily initiated and interrupted, as desired, without requiring the operator to remove his hands from the work.

The invention is of course not to be limited to the specific construction and organization of the illustrative machine hereinbefore described and shown in the drawings. On the contrary, as will appear to those familiar with the art, the invention may be variously embodied. It is not essential that all of the features of the invention be employed conjointly since they may be used to advantage separately in the various combinations and sub-combinations defined in the subjoined claims.

Claims:

1. In a folding machine, the combination of a creaser, a movable folder co-operating therewith, a presser constructed and arranged to operate on the fold subsequently to the action of the folder, mechanism for actuating the folder, and means whereby the position of the folder with respect to the creaser may be adjusted.
2. In a folding machine, the combination of a work support, folding means; and a yieldingly supported substantially integral face gage and edge gage adapted to permit folding of a portion of said edge.
3. In a folding machine, the combination of a supporting table over which the work is

fed intermittently, a creaser for determining the line of fold, means for folding the margin of the work upon said line, means for pressing the fold so formed and means for adjusting the creaser to vary the location of the line of fold. 70

4. In a folding machine, the combination of a work support over which the work is fed intermittently, a feed wheel having a flange extending above the normal feeding surface of said wheel whereby a comparatively wide angle is formed between said flange and surface, and a comparatively thin creaser arranged at an inclination so as to engage the work at the apex of said angle 80 and leave it free on both sides.

5. In a folding machine, the combination of progressively acting folding means; and means to define the line of the fold, automatically adjustable by varying thicknesses 85 of the work toward and from the edge of the work.

6. In a folding machine, the combination of progressively acting folding means; and means for preparing the work for said folding means, operating to define the line of the fold, said defining means being adjustable away from the edge of the work responsive to increased thickness of the work. 90

7. In a folding machine, the combination 95 of folding mechanism; starting-and-stopping means therefor; edge cutting mechanism; starting-and-stopping means therefor; and controlling means common to both said starting-and-stopping means. 100

8. In a folding machine, the combination of a work support, combined feeding and creasing means adapted to crease an independently raised work edge, a presser movable to and from the work, slitting means to 105 make a drawing cut in said edge actuated by the presser actuating means, and edge folding means.

9. In a folding machine, the combination of a supporting table over which the work 110 is fed intermittently, stationary means acting to lift the margin of the work as it is fed, a movable folder for folding the upturned margin down upon the body of the work, and means for pressing the fold, said 115 means being arranged to act successively.

10. In a folding machine, the combination of a supporting table over which the work is fed intermittently, a plow against the curved face of which the margin of the work 120 is drawn, a creaser for determining the line of fold, a folder for bending the margin of the work over the creaser, and a presser for pressing the fold.

11. In a folding machine, the combination 125 of a horizontal supporting table over which the work is fed intermittently, a creaser, a spring tending to hold said creaser against the work but permitting it to move toward and away from the line of fold, means for 130

varying the tension of the spring, a folder movable in a path at an angle to the direction of movement of the creaser, and means for pressing the fold.

12. In a folding machine, the combination of a supporting table over which the work is fed intermittently, a creaser, a spring tending to hold said creaser against the work but permitting it to move bodily toward and away from the line of fold, a folder movable in a path at an angle to the direction of bodily movement of the creaser, means for pressing the fold and manual means for moving the creaser in opposition to the 15 spring.

13. In a folding machine, the combination of a supporting table over which the work is fed intermittently, a creaser, a pivot about which said creaser is angularly movable to 20 ward and from the line of fold, a spring tending to move said creaser toward said line, means for adjusting the creaser away from the line, means for folding the margin of the work about said line, and means for 25 pressing the fold.

14. In a folding machine, the combination of a supporting table over which the work is fed intermittently, a creaser for determining the line of fold, a presser, means for 30 moving said presser toward and from the work, slitting means arranged to make a draw cut in the margin of the work, means for folding said margin, and means for connecting said slitting means with said presser 35 moving means.

15. In a folding machine the combination of a horizontal supporting table over which the work is fed intermittently, a creaser, a spring tending to hold said creaser against 40 the work but permitting it to move substantially obliquely toward and away from the line of fold, a folder movable in a path at an angle to the direction in which the creaser extends, and means for pressing the 45 fold.

16. In a folding machine the combination of a supporting table over which the work is fed intermittently, a creaser, a spring tending to move said creaser toward said 50 support, a movable folder coöperating with the creaser to form the fold and means for pressing the fold, said creaser being readily movable away from the support to permit insertion of the work.

17. In a folding machine the combination of a supporting table, means for feeding a piece of material intermittently over said table, a creaser for determining the line of fold, a folder coöperating with the creaser 60 to form the fold, and a presser for pressing the fold, said folder being arranged to operate during the pauses in the feed.

18. In a folding machine the combination of a supporting table over which the work 65 is fed intermittently, a creaser for deter-

mining the line of fold, a folder, means for moving said folder intermittently transversely of the line of fold into operative position, a presser located at one side of the folder, and means for bringing said presser 70 intermittently into contact with the fold.

19. In a folding machine, the combination of a creaser, a movable folder coöperating therewith, a presser for completing the fold, and mechanism for actuating the folder including yielding adjustable means for limiting the pressure of the folder. 75

20. In a folding machine, the combination with folding instrumentalities, of a reciprocatory presser carrying member having a 80 housing formed at its upper end, a pin disposed within the housing, a presser comprising a sleeve slidable on the pin, and a presser arm projecting outwardly from the sleeve, and a spring arranged to permit yielding 85 of the presser in case a thick place in the work is encountered.

21. A step-by-step folding machine having, in combination, a cutter for slitting the margin of a piece of material, a folder 90 located at one side of the cutter, a presser located at one side of the folder, a creaser about which the slit margin is bent by the folder, means for actuating said cutter, folder and presser, and means for feeding 95 material thereto.

22. A machine of the class described having, in combination, means for feeding a piece of material intermittently into position to have its margin operated upon, 100 means for progressively slitting said margin to form a plurality of tongues, and means for folding said tongues one by one during the pauses in the feed, said means comprising a creaser about which each tongue is 105 bent.

23. A machine of the class described having, in combination, means for feeding a piece of material intermittently into position to have its margin operated upon, a 110 creaser and a folder past which the material is fed, means for causing relative movement between the folder and creaser to form the fold, and means for pressing the fold.

24. A machine of the class described having, in combination, folding and feeding mechanism comprising a folder held from movement in the line of feed, a combined feeding member and creaser, and means for actuating said folder and combined member. 115

25. A folding machine for doubling the edge of sheet material in a series of steps comprising a support for the stock, a fold guide arranged to bear upon the surface of stock lying on said support, a turning device 120 movable across the line of fold established by said guide, and means for feeding the stock step by step in the direction of the line of fold, said guide serving to maintain such line after each step of the feed. 125

26. A step-by-step folding machine having, in combination, a cutter for slitting the margin of a piece of material, a folder located at one side of the cutter, a presser located at one side of the folder, a creaser across the edge of which the folder moves, means for actuating said cutter, folder, creaser and presser, and means for feeding material thereto.
- 10 27. A machine of the class described having, in combination, means for feeding a piece of material intermittently into position to have its margin operated upon, and means for progressively folding said margin, said last-named means including a folder and a creaser across the edge of which the folder moves.
- 15 28. A machine of the class described having, in combination, means to feed a piece of material intermittently into position to have its edge operated upon, and means for progressively folding said edge, said last-named means including a rest and a folding finger movable toward the rest for bending the edge of the material about the edge of said rest.
- 20 29. A machine of the class described having, in combination, means for feeding a piece of material intermittently into position to have its margin operated upon, a slitting knife, a folder located beside said knife, a creaser located beside said folder and arranged to coöperate with said folder to form a fold, a presser located beside said folder, actuating mechanism for said folder and presser, a continuously reciprocating member, and means for connecting said knife with said member and for disconnecting it therefrom at will during the operation of the machine.
- 25 30. A machine of the class described having, in combination, means for feeding a piece of material intermittently into position to have its margin operated upon, a slitting knife, a folder located to one side of the knife in the line of feed, a creaser located in operative relation with respect to said folder and arranged to coöperate with said folder to form a fold, a presser located to one side of the folder in the line of feed, actuating mechanism for said folder and presser, a continuously reciprocating member, and means for connecting said knife with said member and for disconnecting it therefrom at will during the operation of the machine.
- 30 31. A machine of the class described having, in combination, means for feeding a piece of material intermittently into position to have its margin operated upon, a slitting knife, a folder located to one side of the knife in the line of feed, a creaser located in operative relation with respect to said folder and arranged to coöperate with said folder to form a fold, a presser,
- 35 40 45 50 55 60 65 70 75 80 85 90 95 100 105 110 115 120 125 130
- actuating mechanism for said folder and presser, a continuously actuated member, and means for connecting said knife with said member and for disconnecting it therefrom at will during the operation of the machine.
32. A machine of the class described having, in combination, means for feeding a piece of material intermittently into position to have its margin operated upon, a cutter for slitting the margin, a folder, a creaser about the edge of which the margin is bent by the folder, a presser, means for actuating said cutter, folder and presser, and means for varying the extent of the intermittent feed movements.
33. In a folding machine the combination of a supporting table over which the work is fed intermittently, a folded guide, a spring tending to hold said fold guide against the work but permitting it to move bodily toward and away from the line of fold, a folder movable in a path at an angle to the line of the fold, means for pressing the fold, and manual means for moving the fold guide in opposition to the spring.
34. In a folding machine the combination of a supporting table over which the work is fed intermittently, a creaser, a pivot about which said creaser is angularly movable toward and from the line of fold, a spring tending to move said creaser toward said line, means for folding the margin of the work about said line, and means for pressing the fold.
35. A machine of the class described having, in combination, means for feeding a piece of material intermittently into position to have its margin operated upon, a creaser, a folder constructed and arranged to coöperate with the creaser and being movable in a path at an angle to the line of the fold, slitting mechanism, and means for varying the distance between the slits produced by said mechanism.
36. A machine for folding and pressing a piece of material having, in combination, a supporting table over which the material is fed intermittently and means for progressively folding the margin of said piece, said folding means including a folder and a creaser which coöperate to form the fold partially preparatory to the pressing operation.
37. In a folding machine the combination of a horizontal supporting table over which the work is fed intermittently, a creaser, a spring tending to hold said creaser against the work but permitting it to move substantially obliquely to the plane of the work and toward and away from the line of fold, and a folder movable in a path at an angle to the direction in which the creaser extends.
38. In a folding machine the combination

- of a supporting table over which the work is fed intermittently, a creaser for determining the fold line, a pivot disposed above and at one side of the fold line and about which said creaser is angularly movable toward and from the fold line, a spring tending to move the creaser toward said line, and means for folding the margin of the work about said line. 40
39. In a folding machine a support for the work, a fold presser, a fold presser housing extending through said support, mechanism located beneath said support for operating said housing, yielding means for causing said fold presser to move toward said support with said housing, and means for varying the tension of said yielding means. 45
40. In a folding machine, the combination of a work support, a fold presser housing extending below the plane of the work on the support, a fold presser having movement in said housing, a resilient connection acting on said fold presser and said fold presser housing, and means for adjusting the normal position of said fold presser. 50
41. In a folding machine, the combination with a work support, of a fold presser, a housing therefor with respect to which the presser is movable, mechanism for moving the housing and thereby the presser to effect the pressing operation, a spring for maintaining said presser and housing normally in a predetermined relation, and means for adjusting the spring to regulate the action of the presser on the fold. 55
42. In a folding machine the combination of a supporting table over which the work is fed intermittently, a creaser, a spring tending to move said creaser toward the support, a folder coöoperating with the creaser to form the fold, means for pressing the fold, and a lever fulcrumed on the frame of the machine and arranged to engage said creaser whereby said creaser may be raised at will. 60
43. In a machine for folding pliable material the combination of an edge-turning cutter block, a knife, feeding means to feed the work upon said cutter block to the knife, a folding member comprising a narrow inwardly and downwardly acting finger to fold said turned edge, and a hammer arranged to engage said edge. 65
44. A step-by-step folding machine having a work table, folding instrumentalities, a folded presser movable transversely to the folded edge above the work table, a fold presser housing, actuating mechanism located beneath the work support for operating the housing and being connected thereto beneath the support, and an adjustable spring for moving the fold presser toward the work when the housing is moved in one direction by its actuating mechanism. 70

In testimony whereof, I have signed my name to this specification, in the presence of two subscribing witnesses.

CHARLES P. STANBON.

Witnesses:

ROBERT H. KAMMLER,
FREDERIC GILBERT BAUER.

It is hereby certified that in Letters Patent No. 1,120,556, granted December 8, 1914, upon the application of Charles P. Stanbon, of Saugus, Massachusetts, for an improvement in "Folding-Machines," errors appear in the printed specification requiring correction as follows: Page 2, line 71, for the word "arms" read *arm*; page 9, line 64, and page 10, line 56, for the word "folded" read *fold*; and that the said Letters Patent should be read with these corrections therein that the same may conform to the record of the case in the Patent Office.

Signed and sealed this 26th day of January, A. D., 1915.

[SEAL.]

R. F. WHITEHEAD,

Acting Commissioner of Patents.
